United States Patent Office

Des. 186,775
Patented Dec. 1, 1959

186,775

FISHING FLOAT

Roy W. Spencer, New Orleans, La.

Application May 8, 1959, Serial No. 55,827

Term of patent 14 years

(Cl. D31—4)

FIG-1

FIG-2

FIG-3

FIG-4

Fig. 1 is a side elevational view of a fishing float showing my new design;

Fig. 2 is a left end perspective view thereof;

Fig. 3 is an end elevational view thereof taken from the right of Fig. 1; and

Fig. 4 is an elevational view thereof taken from the left of Fig. 1.

I claim:

The ornamental design for a fishing float, as shown.
